(57) CLAIM

The ornamental design for a mason jar, as shown and described.

DESCRIPTION

FIG. 1 is a perspective view of the top, front, and right side of a mason jar;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines are shown for the purpose of illustrating unclaimed portions of the mason jar and form no part of the claimed design.
